CLAIM

The ornamental design for an illuminated storage box with light-emitting diodes, as shown and described.

DESCRIPTION

FIG. 1 is a top left side perspective view of the illuminated storage box having light emitting diodes of this invention. FIG. 2 is a top right side perspective view of the illuminated storage box of this invention.

FIG. 3 is a top view of the illuminated storage box having light emitting diodes of this invention.

FIG. 4 is a bottom view of the illuminated storage box having light emitting diodes of this invention.

FIG. 5 is a right side view of the illuminated storage box having light emitting diodes of this invention with the left side view being a mirror image of the right side view.

FIG. 6 is a front view of the illuminated storage box having light emitting diodes of this invention; and,

FIG. 7 is a back view of the illuminated storage box having light emitting diodes of this invention.

The broken line showing represents portions of the article not claimed and forms no part of the claimed design.
